UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

CORRUGATION IN HOPPER DOORS FOR RAILWAY CARS.

Application filed August 17, 1925. Serial No. 50,726.

The invention relates to a railway dump car having a "door" forming a part of the car for retaining the load therein, which door is provided with hinges adjacent one 5 of its sides and is capable of being "dropped" or swung open so that the load in discharging slides or passes over the upper surface of the door. Any means of raising the door to the closed position and any means for 10 locking and releasing the door may be employed with my device.

Experience has shown that a slight projection on the upper surface of such a door causes the discharging load to bank up and 15 seriously retard the unloading of the car sometimes completely obstructing the opening and at other times causing some of the material to remain in the car. It is essential that the entire load be discharged when the 20 doors are dropped in order to conserve time when the cars are being used to ballast a main line track, or to eliminate the necessity of maintaining men to remove any small portion of the load that remains in the car 25 after the doors are dropped.

The relative position of the rail, the truck (and other parts of the car) and service conditions also regulate the inclination of the door after it is dropped, so that it is seldom 30 possible to allow the doors to drop to a vertical position; in fact, in a drop bottom gondola car the doors are positioned only about thirty degrees from a horizontal plane when in the open position.

35 A door for this purpose must be very strong and durable because:

First: It is part of the floor of the car and as such must sustain the load as well as the impact blow when the car is in motion.

40 Second: The car is frequently loaded from chutes or tipples from a height of ten feet or more, causing the load to be dropped directly upon the doors.

Third: Clam shell buckets are frequently 45 used to unload such cars and it is not uncommon for these buckets to rest upon and drag over the doors.

Fourth: When the door suddenly comes to rest after being dropped it is not only 50 subjected to a severe shock but it must sustain the severe impact thrust of the load which, of course, follows the door.

Fifth: As the load is theoretically equally 55 distributed, the door must be strong over its entire area and must be capable of transmit-

ting the resulting strains to the car body, without much deflection and no substantial distortion. Any bending of the door or drooping of the corners would cause a leak of the lading, especially of such fine material as sand, chats, etc. Any bending or warping might interfere with the complete closing and locking of the door. 60

As it costs as much to haul a ton of car as it does to haul a ton of paying freight, 65 it is imperative that the car and any part thereof be as light as possible. Furthermore, the total weight of car and freight is determined by the strength of certain standard axles, so that the lighter the car 70 the greater amount of freight a given car will be allowed to carry.

Various means have been used to strengthen a plate metal door to meet the service conditions. Reinforcements have been secured 75 to the door, thus materially increasing its weight which is objectionable. Various integral reinforcements (such as corrugations) have been formed in metallic plates, which, however, interfere with the discharge 80 of the loading or have other objectionable features.

In my design the door is provided with a plurality of preferably parallel corrugations which extend from the hinge side of 85 the door toward the outer side thereof, or in other words, in the direction of the moving lading while discharging. Owing to the peculiar and particular relation of the corrugations to the original plane of the plate 90 and to each other, neither the corrugations nor their terminations present any pockets or projections to interfere with the free discharge of the lading which is accomplished without sacrificing strength as the 95 corrugated plate is of maximum strength (and of equal strength) between lines adjacent the inner and outer sides of the door.

One of the objects of the invention is to obtain a strong durable door for a load discharging freight car made of a metallic plate formed with integral corrugations which are positioned approximately parallel to the direction of discharge of the lading but are of such configuration as not to interfere with the movement of the cargo when leaving the car. 100

Another object is to obtain a door having the integral corrugations formed so that the neutral axis is substantially midway between 105

the planes bounding the apexes of the corrugations and yet the corrugations will not interfere with the discharge of the cargo.

Another object of the invention is to form reinforcing corrugations in a metallic plate hopper door which extend parallel to the direction of discharge of the lading but do not present any pockets or projections to interfere with the movement of the lading leaving the car.

The advantages of my door are applicable to any door of a freight car over which the lading moves when being discharged from the car, such as drop bottom general service cars (used in the drawings), hopper cars, swinging side doors or hopper bottom coal cars, etc.

In the drawings:

Fig. 1 shows a part of a railway car with my device applied thereto.

Fig. 2 is a section on line 2—2 of Fig. 1.

Fig. 3 is similar to Fig. 2 but shows the door in open position.

Fig. 4 is a detail drawing of the door shown in Figs. 1, 2 and 3.

Fig. 5 is a section on line 5—5 of Fig. 4.

Fig. 6 is a section on line 6—6 of Fig. 4.

Fig. 7 is a section on line 7—7 of Fig. 4.

Fig. 8 is a section on line 8—8 of Fig. 4.

Fig. 9 is a section on line 9—9 of Fig. 4.

Fig. 10 is similar to Fig. 5 and shows a modification.

Fig. 11 is similar to Fig. 7 and shows a modification.

To illustrate one adaptation of my device, I have shown a so-called "general service" drop bottom gondola car wherein the major portion of the floor consists of drop doors. The door openings are surrounded by the center construction, side wall and cross dia-phragms. In normal or closed position the door completely closes this opening and, in fact, is a trifle larger on all sides than the opening so as to provide a lap joint between the door and the car frame members. The hinge-beams are hinged to the center construction and are supported adjacent the side wall by the raising or locking mechanism. Any convenient stop, such as 2, may be used to limit the downward movement of the door.

The door is made of a metallic (preferably steel) plate formed with a plurality of integral corrugations or reinforcing ribs preferably (though not necessarily) terminating within the sides of the door so as to leave a flat margin 4 surrounding the corrugated portion of the plate. This flat margin is in the original plane of the plate and is in a single plane at all four sides of the door so as to simplify application of the door to the car as this margin is in contact with the adjacent car parts and forms the seal for the lading. The door may be made without this flat margin and still come with

in the scope of the broader claims appended hereto.

I provide a plurality of downwardly projecting corrugations 5 having their maximum depth adjacent one side (preferably the hinge side) of the door and another plurality of corrugations 6 projecting upwardly having their maximum depth adjacent the opposite side of the door. These corrugations are preferably positioned alternately and preferably merge into each other to form a sinuous configuration. The apexes of these oppositely projecting groups of corrugations are in parallel planes 7—8 (Fig. 2) between the lines of maximum depth of the upwardly and downwardly projecting corrugations, respectively, which planes are positioned obliquely to the original plane 9 of the plate (and the margins). Any contour of corrugations may be used and it is not essential that they merge into each other, but it is desirable that the downwardly projecting corrugations decrease in depth consistently with the upwardly projecting corrugations so that the bounding planes 7—8 will be parallel and so that the corrugated door will be of uniform strength for the major portion of its surface. Furthermore, with such an arrangement the neutral axis of the corrugated portion of the plate (or door) is midway between the bounding planes, and as steel is substantially equal in tensile and compressive strength, this gives a balanced beam.

Fig. 10 shows a construction wherein the corrugations 5—6 merge into perpendicular flanges 10—11 provided at the opposite sides of the door.

Fig. 11 shows a construction wherein the corrugations 5—6 do not merge into each other and yet have the other desirable features.

In this application, as well as my application Serial No. 50,044, filed August 13, 1925, I have disclosed but not claimed, a door having a plurality of parallel downwardly projecting embossments formed therein with flat places between some of said embossments having hinges parallel to said embossments and secured to the flat places, which structure, however, is claimed in my co-pending application Serial No. 50,043, filed August 13, 1925.

I claim:

1. A door for a railway dump car made of a metallic plate formed with a plurality of corrugations terminating within the sides of the door so as to leave a flat margin in a single plane surrounding said corrugations projecting upwardly and downwardly with the apexes of the oppositely projecting corrugations in parallel planes positioned obliquely to said flat margin.

2. A door for a railway dump car made of a metallic plate formed with a plurality

- of corrugations terminating within the sides of the door so as to leave a flat margin in a single plane surrounding said corrugations projecting alternately upwardly and downwardly with the apexes of the oppositely projecting corrugations in parallel planes positioned obliquely to said flat margin. 5
3. A door for a railway dump car made of a metallic plate formed with a plurality of corrugations terminating within the sides of the door so as to leave a flat margin in a single plane surrounding said corrugations, said corrugations projecting upwardly and downwardly with the apexes of the oppositely projecting corrugations in parallel planes positioned obliquely to the original plane of the plate. 10
4. A door for a railway dump car made of a metallic plate formed with a plurality of corrugations terminating within the sides of the door so as to leave a flat margin in a single plane surrounding said corrugations, said corrugations projecting alternately upwardly and downwardly with the apexes of the oppositely projecting corrugations in parallel planes positioned obliquely to the original plane of the plate. 15
5. A door for a railway dump car made of a metallic plate formed with a plurality of corrugations terminating within the sides of the door so as to leave a flat margin in a single plane surrounding said corrugations, said corrugations projecting alternately upwardly and downwardly with the apexes of the oppositely projecting corrugations in parallel planes positioned obliquely to the original plane of the plate. 20
- 35
6. A door for a railway dump car made of a metallic plate formed with a plurality of corrugations terminating within the sides of the door so as to leave a flat margin in a single plane surrounding said corrugations, said corrugations projecting alternately upwardly and downwardly with the apexes of the oppositely projecting corrugations in parallel planes positioned obliquely to the original plane of the plate, said corrugations merging into each other to form a sinuous configuration. 30
- 40
7. A door for a railway dump car made of a metallic plate formed with a plurality of corrugations terminating within the sides of the door so as to leave a flat margin in a single plane surrounding said corrugations, said corrugations projecting alternately upwardly and downwardly with the apexes of the oppositely projecting corrugations in parallel planes positioned obliquely to the original plane of the plate, said corrugations merging into each other to form a sinuous configuration with the neutral axis substantially midway between said planes. 45
- 55
- the oppositely projecting corrugations in parallel planes positioned obliquely to said flat margin, said corrugations merging into each other to form a sinuous configuration. 60
8. A door for a railway dump car made of a metallic plate formed with a plurality of corrugations terminating within the sides of the door so as to leave a flat margin in a single plane surrounding said corrugations, said corrugations projecting alternately upwardly and downwardly with the apexes of the oppositely projecting corrugations in parallel planes positioned obliquely to said flat margin, said corrugations merging into each other to form a sinuous configuration. 65
- 70
9. A door for a railway dump car made of a metallic plate formed with a plurality of downwardly projecting corrugations having a greater depth adjacent one side of the door than elsewhere, and a plurality of upwardly projecting corrugations having a greater depth adjacent the other side of the door than elsewhere. 75
- 80
10. A door for a railway dump car made of a metallic plate formed with a plurality of downwardly projecting corrugations having a greater depth adjacent one side of the door than elsewhere, and a plurality of upwardly projecting corrugations having a greater depth adjacent the other side of the door than elsewhere, said corrugations positioned alternately. 85
- 90
11. In a railway dump car; the combination of a member and a door hinged thereto, said door formed with a plurality of downwardly projecting corrugations having their maximum depth adjacent the hinge side of the door, and a plurality of upwardly projecting corrugations having their maximum depth adjacent the opposite side of the door having the apexes of the oppositely projecting corrugations in parallel planes positioned obliquely to the original plane of the plate. 95
- 100
12. In a railway dump car; the combination of a member and a door hinged thereto, said door formed with a plurality of downwardly projecting corrugations having their maximum depth adjacent the hinge side of the door, and a plurality of upwardly projecting corrugations having their maximum depth adjacent the opposite side of the door, said corrugations positioned alternately and having the apexes of the oppositely projecting corrugations in parallel planes positioned obliquely to the original plane of the plate. 105
- 110
- 115

VINTON E. SISSON.
